UNITED STATES PATENT OFFICE

JAMES P. DOVEL, OF BIRMINGHAM, ALABAMA, ASSIGNOR TO G. P. DOVEL

LOADING APPARATUS

Application filed November 14, 1925. Serial No. 68,947.

My invention relates to a power loading device which is essentially adapted for the handling of heavy bulk material such as coal, ore and the like, and which is characterized by the provision of a rigid boom adapted to be vertically oscillated and to swing laterally and carrying at its free end a loading device somewhat similar in construction to the clam shell dipper but so mounted and designed that it is adapted to dig into the body of material to be handled responsive to a down swing of the boom and thus to take its load more efficiently and to operate at maximum loading capacity.

More particularly, my invention contemplates certain improvements in the type of power shovel forming the subject matter of Letters Patent No. 1,444,670, which were issued to me on Feb. 6th, 1923, such improvements consisting essentially in the substitution of the new type of dipper for the shovel and the arrangement of the dipper jaws so that they are adapted to dig into the body of the material responsive to a downward swinging motion of the boom, and to assume a position at ground level by which one of the jaws can be used as a scraper to clean up the floor like the shovel in the patent aforesaid.

My invention also comprises the novel details of construction and arrangements of parts, which have in view the simplification of the mounting and manipulation of the dipper jaws on the boom, and which are hereinafter more particularly described and claimed, reference being had to the accompanying drawings which illustrate only the preferred embodiment of my invention and in which:—

Fig. 1 is a side elevation of the complete apparatus with the dipper shown in full line in its partly open elevated position, the dotted lines showing the position the jaws assume when fully open and when lowered to loading position.

Fig. 2 is an enlarged plan view of the end of the boom carrying the dipper.

Fig. 3 is a side elevation of the dipper shown in its lowered closed position after taking its load.

Similar reference numerals refer to similar parts throughout the drawings.

I have illustrated the invention as mounted upon a wheel supported truck 1 having thereon a roller turn buckle table 2 which supports a main power cylinder 3 having mounted thereon overhead guides 4 for the cross head 5, which at each overhung end has swivelled thereto a hinging link 6, each of which in turn is pivotally connected to the rear end 7 of the side spaced members of the boom 8, which members are journaled on the outer ends of a shaft 9 mounted in spaced bearing brackets 10 on opposite sides of the center of the turn table. These booms at their free ends have down turned portions 11 and are cross connected at the end of said portions 11 by a cross brace bolt or shaft 12.

I swing from the free end of the boom a digging dipper somewhat like a clam shell bucket comprising a front jaw 14 and a rear jaw 15. The front jaw has riveted to its sides plates 16 and these in turn are riveted to brackets 17 which have bearings 18 that are pivotally mounted at each end of the shaft 12 between the boom members 11. These brackets carry upwardly and inwardly inclined arms 19 which near the center line of the boom are pivotally connected to an eye 20 at the forward end of a piston rod 21 adapted to be operated by a piston reciprocable in a cylinder 22 mounted by means of trunnions 23, between the boom members 8 and adapted to rock to accommodate itself to the angular movement of the arms 19.

The rear dipper jaw 15 is likewise provided with side plates 24 and to these plates are riveted the arms 25 which project vertically and have bearings 26 which are hung from stud bolts 13 mounted in the boom members 8. Each arm 25 is connected by a pair of links 27 to the adjacent lever arm 19 near its point of connection to the dipper member 14 and at a point remote from the pivot 13 for the dipper jaw. In this manner the two dipper jaws are caused to move simultaneously but differentially to open and close the dipper responsive to the admission of fluid pressure by a control valve 28 into the cylinder 22. In like manner the boom is swung vertically by

means of the control valve 29, and the table is caused to rotate by a drive from the motor 30.

It is apparent that the motion transmitted by cylinder 22 to the lever arms 11 will be highly multiplied by the leverage factors present when transmitted through links 27 to the supporting arms 25 of the rear dipper jaw 15, and that this rear jaw will have a relatively small movement as compared with that of the front dipper jaw 14. The purpose of this is to bring these jaws as nearly as possible to vertical position when the boom is swung down so that their edges will be adapted to dig powerfully downwardly into the body of material to be handled thereby causing the dipper to take its full capacity load and to do this largely responsive to the falling weight of the dipper itself assisted by a power stroke applied through the links 6 from the main cylinder 3 to the boom. In closing the bucket the rear jaw 15 moves in slowly but with great power towards the upper jaw and thus the requisite leverage is available to close the dipper against very heavy interference. It is also important to note that when the dipper is fully open and dropped to the grade level, the lower jaw will stand in a scraping position in contact with the ground while the upper jaw will be raised substantially above the ground level. This is indicated more clearly by the dotted lines showing the position of the dipper jaws when lowered in Fig. 1. The importance of this feature lies in the fact that the lower dipper jaw is thus in position to act like a shovel or scraper so as to clean up the ground and to shovel up material thereon as the machine moves forward, and in this respect it is capable of functioning very much like the shovel shown in my patent aforesaid but always with the added advantages that the jaws can be closed to grip their load and to hold it until ready for discharge into a car or elsewhere. The advantage of having the power cylinder 3 acting to force the boom down enables me to hold the bucket jaws positively against the material while closing them, and I am able to put the full weight of the machine on the buckets in this way so as to force them to take a full load where very bulky heavy material is to be handled such as muck ore or man-sized or large lumps of limestone. The machine will handle such large bulky material because the lower jaw can be pushed under a large lump and get a sufficient purchase to enable a grip from the upper jaw to hold the lump in position between the jaws so that it can be lifted and handled. The control of the apparatus for raising and lowering the boom and for swinging the boom on the turn table will be well understood by those skilled in the art and need not be described in detail here.

The apparatus as a whole presents a loading device of great simplicity in construc-

tion which is rugged and strong and has parts readily replaceable and which has proven of marked advantage in the loading of heavy resistance material like lump ore, stone, etc.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

1. In a loading apparatus, a rigid swinging boom pivoted thereon free to swing vertically, power means to swing the boom, dipper jaws depending from and directly hinged to the free end of the boom, and operating means for moving the jaws into full open position and substantially vertical whereby said jaws may be forced downwardly into the material to be loaded by the power actuated down swing of the boom, said operating means comprising a power cylinder mounted on the boom, and having a piston operated rod operatively connected to one of the dipper jaws, and links connecting the jaws for joint operation responsive to said power cylinder.

2. A loading apparatus, comprising a rigid boom mounted free to swing vertically, a dipper comprising front and rear jaws hinged at different points to and dependent from the free end of said boom, a power cylinder mounted on the boom and having a piston rod connected to one dipper jaw, and links connecting said latter jaw to the other jaw.

3. A loading apparatus comprising a rigid boom mounted free to swing vertically, a dipper comprising front and rear jaws having spaced hinge connections to the free end of said boom, a power cylinder mounted on the boom and connected to the outer dipper jaw, and links connecting said jaws with their point of connection to the inner jaw further from its hinge than the point of connection to the outer jaw.

4. In a loading apparatus, a rigid swinging boom pivoted thereon free to swing vertically, power means to swing the boom, dipper jaws depending from and directly hinged to the free end of the boom, operating means for moving the jaws into full open position and substantially vertical whereby said jaws may be forced downwardly into the material to be loaded by the power actuated swing of the boom, and means included in the operating means to open the forward jaw faster than the rear or scooping jaw.

5. In a loading apparatus, a rigid swinging boom pivoted thereon free to swing vertically, power means to swing the boom, dip-

per jaws hinged to swing from spaced axes mounted directly and transversely in the free end of the boom, and operating means for moving the jaws into full open position and adapted to move the outer jaw sufficiently 5 above the plane of the lower edge of the inner jaw to adapt the latter to serve as a scraper when the apparatus is moved forward with the dipper jaws open and the boom lowered to bring said inner jaw to ground level.

10 6. In a loading apparatus, a rigid boom, a pair of dipper jaws pivoted to the boom on spaced centers, an operating arm rigidly connected to one of the jaws, a link connection between said operating arm and the other 15 jaw, and power means for actuating the operating arm.

7. In a loading apparatus, a rigid boom, a pair of dipper jaws pivoted to the boom on spaced centers, an operating arm rigidly connected to one of the jaws, a link connection between said operating arm and the other 20 jaw, and rigid reciprocable power actuated means for actuating the operating arm.

25 8. In a loading apparatus, a rigid boom, a pair of dipper jaws pivoted to the boom on spaced centers, an operating arm rigidly connected to one of the jaws, a link connection between said operating arm and the other 30 jaw, rigid reciprocable power actuated means for actuating the operating arm, and other power means for swinging the boom through a vertical plane.

35 9. In a loading apparatus, a rigid boom, a rear dipper jaw having an upwardly extending rigid arm pivotally connected directly to the boom toward the outer end thereof, a forward dipper jaw pivotally connected directly to the end of the boom, an upwardly extending operating arm rigidly connected 40 to the forward dipper, and a link connection between the operating arm and the upwardly extending arm of the rear dipper jaw.

45 10. In a loading apparatus, a rigid boom, a rear dipper jaw having an upwardly extending rigid arm pivotally connected directly to the boom toward the outer end thereof, a forward dipper jaw pivotally connected directly to the end of the boom, an upwardly 50 extending operating arm rigidly connected to the forward dipper, a link connection between the operating arm and the upwardly extending arm of the rear dipper, and rigid reciprocable power actuated means for actuating the operating arm.

55 In testimony whereof I affix my signature.
JAMES P. DOVEL.
